UNITED STATES PATENT OFFICE.

OTTO D. NORMAN, OF SPENCER, WEST VIRGINIA.

DRILLING-MACHINE.

1,376,028.

Specification of Letters Patent. Patented Apr. 26, 1921.

Application filed April 19, 1919. Serial No. 291,245.

To all whom it may concern:

Be it known that I, OTTO D. NORMAN, a citizen of the United States, residing at Spencer, in the county of Roane and State of West Virginia, have invented certain new and useful Improvements in Drilling-Machines, of which the following is a specification.

This invention relates to drilling machines, such as used in drilling wells, and an object of the invention is to provide a well drilling machine structure wherein an internal combustion engine of any approved type is employed, both for tractive power and for drilling power, of the machine, and further to provide a novel form of transmission mechanism for transmitting the power from the internal combustion engine to the drilling mechanism operating pulley and also to the traction wheel operating structure, the latter being normally idle from connection with the prime mover, and including a sprocket which is mounted upon the shaft that carries the pulley for operating the drilling mechanism, and to provide a pair of removable pins adapted to extend through the sprocket and into the hub of a pulley for operatively connecting the sprocket to the pulley to operate the speed change gears and transmit power to the traction wheels of the device.

A further object of the invention is to provide in a well drilling machine utilizing an internal combustion engine as power, means whereby the magneto operating shaft of the internal combustion engine may be connected direct to the blower utilized in the well drilling machine for operating the blower by operation of the engine.

Other objects of the invention will appear in the following detailed description taken in connection with the accompanying drawings, forming a part of this specification, and in which drawings:

Figure 1 is a side elevation of the improved drilling machine.

Fig. 2 is a top plan of the chassis of the drilling machine showing the connection between the engine and drives.

Fig. 3 is a fragmentary side elevation of the drilling machine showing the controls.

Fig. 4 is a fragmentary view illustrating the manner of connection between the magneto shaft of the engine and the blower of the drill.

Fig. 5 is a section on the line 5—5 of Fig. 2.

Fig. 6 is a section on the line 6—6 of Fig. 5.

Fig. 7 is a detail plan of the speed change 60 gears.

Fig. 8 is a fragmentary section showing the manner of mounting the speed change gear operating lever.

Fig. 9 is a top plan of the modified form 65 of the invention.

Fig. 10 is a fragmentary side elevation of the drilling machine illustrating the control of the modified form.

Fig. 11 is a detail section illustrating a 70 detachable connection of clutch operating levers used in the drilling machine.

Referring more particularly to the drawings, wherein like characters indicate like and corresponding parts throughout the 75 several views, A indicates the supporting frame as an entirety of the drilling machine which frame carries the usual drilling mechanism indicated at B and including the usual form of tower C.

An internal combustion engine 1 of any 80 approved type is supported by the chassis or supporting frame A of the well drilling machine and the power shaft 2 thereof has a beveled pinion 3 mounted upon its outer end, which beveled pinion meshes with a beveled gear 4. The beveled gear 4 is mounted upon a shaft 5 which extends transversely of the frame A and has a pulley 6 keyed thereon. The pulley 6 is connected to the operating 85 mechanism B of the well drilling structure by a belt 7 for operating the well drilling mechanism B by operation of the internal combustion engine 1. The frame A carries the usual front axle 10 upon which are mounted the front wheels 11 and it also carries the rear axle 12 upon which the rear traction wheels 13 of the well drilling machine are mounted. These traction wheels 13 have crown gears 14 carried thereby 90 which mesh with pinions 15. The pinions 15 are mounted upon a shaft 16 which extends transversely of the frame A and which carries the gears 17 and 18 which coat with gears 19 and 20 carried by a shaft 21 to provide the speed change gears for changing the speed of travel of the well drilling machine. The shaft 21 is positioned above the shaft 16 and it has a sprocket 22 mounted thereon about which a sprocket chain 23 95

100 which mesh with pinions 15. The pinions 15 are mounted upon a shaft 16 which extends transversely of the frame A and which carries the gears 17 and 18 which coat with gears 19 and 20 carried by a shaft 21 to provide the speed change gears for changing the speed of travel of the well drilling machine. The shaft 21 is positioned above the shaft 16 and it has a sprocket 22 mounted thereon about which a sprocket chain 23 110

travels. The sprocket chain 23 also travels about a sprocket 24 which is loosely mounted upon the shaft 5, permitting the shaft 5 to rotate independently of rotation of the sprocket 24 during the operation of the well drilling mechanism. However, when it is desired to move the well drill from one place to another, the belt 7 is thrown off the pulley 6 and a plurality of pins or bolts 25 are inserted through the openings 26 formed in the sprocket 24 and into openings 27 formed in the hub 28 of the pulley 6, thus operatively connecting the sprocket 24 with the shaft 5, to rotate the said sprocket and consequently the shaft 21 and shaft 16 by the operation of the internal combustion engine 1.

A dual control for the fuel supply or gas to the engine 1 is provided, it including a lever 30 positioned at the rear end of the machine, and a second lever 31 which is pivotally mounted as shown at 32 at the forward end of the machine and is connected by means of a rod 33 to the carburetor of the engine for controlling the supply of fuel to the latter. Suitable quadrants are provided for maintaining the levers 30 and 31 in adjusted positions. A clutch control lever 34 is also positioned at the forward end of the machine, being connected by means of a shaft 35 and suitable links as shown at 36 with the clutch operating arm 37. The clutch operating arm 37 also has a bar or rod 38 connected thereto which is in turn adjustably connected as shown at 39 to the brake lever 40. The rod or lever 38 extends to the rear end of the machine, where a hand lever 41 is provided for operating it. When drilling a well with the machine, the brake lever 40 which is pivotally connected to the frame A is disconnected, to permit operation of the clutch independently of the brake.

The magneto driving shaft 43 of the internal combustion engine 1 has a pulley 44 mounted thereon about which a belt 45 travels. This belt 45 also travels about the operating pulley 46 of the blower 47 which is used to provide a draft for forge (not shown in the drawings) used in heating bits, etc.

The engine 1 has associated therewith the usual speed change gears such as are employed in power plants of motor vehicles, providing the necessary or desired change of speed ahead or reverse for controlling the operation of the drilling mechanism B while the speed change gears 17, 18, 19 and 20 form a second set of speed change gears for controlling the drive of the traction wheels 13. A lever 48 is provided, for controlling the usual speed change gears of the engine, and this lever is pivotally supported by a bearing member 49, which bearing member is pivotally connected to a pivotal support or arc 50. The hand grip 51 of the lever 48

is positioned at the rear end of the machine so that it may be conveniently reached and operated by an operator standing upon the platform 52. The levers 30 and 41 are also positioned for convenient reach and operation from the platform 52.

When it is desired to operate the well drilling mechanism B by the engine 1, the belt 7 is passed about the pulley 6 and about the operating pulley 53, of the mechanism B, after which the lever 48 may be shifted to provide the proper speed of rotation of the shaft 2 by operation of the engine 1 and the power is transmitted from the shaft 2 to the shaft 5, and consequently to the pulley 6.

When it is desired to transport or move the well drilling machine, the belt 7 is slipped off the pulley 6 and the pins 25 are inserted through the openings 26 into the openings 27 for connecting the sprocket 24 operatively with the shaft 5. The power is transmitted from the shaft 5 through the sprocket 24, chain 23, to the shaft 21, where the tractive speed of the well drilling machine may be regulated by the shifting of either of the gears 19 or 20 into the respective gears 17 and 18, thus transmitting the motion to the shaft 16 and from this shaft to the traction wheels 13, through the medium of the pinion 15 and the gears 14.

In Figs. 9 and 10 of the drawings, the shaft 5^a has a brake pulley or wheel 41^a mounted thereon upon the opposite side of the beveled gear 4^a from the pulley 6^a and a friction brake band 40^a extends about the periphery of said brake pulley or wheel, having one end connected to a suitable support 42^a and the other end connected to the wrist or crank 43^a. The shaft 44^a upon which the crank 43^a is formed is supported by suitable bearings 45^a and is extended upwardly as clearly shown in Figs. 9 and 10 of the drawings, being connected to a rod 46^a which extends rearwardly along the chassis of the drilling machine and has its rear end connected to the rod 47^a which extends rearwardly across the rear end of the chassis and has a hand lever 41^b connected thereto for operating the friction brake band 40^a. This rod 47^a also has the longitudinally extending bar 38^a connected thereto by means of which the clutch mechanism of the power plant is operated, and thus through the medium of this mechanism, the brake band 40^a will be moved into gripping engagement with the brake wheel 41^a simultaneously with the operation of the clutch mechanism of the power plant.

The clutch operating lever 37^a has a control lever 34^a connected thereto through the medium of a series of links 36^a as disclosed and specified in the preferred form of the invention which control lever extends to the rear end of the drilling machine. How-

ever, during the moving of the drilling machine from one place to another or during the traction of the drilling machine, it is desirable to have this control lever 34^a disconnected from the clutch lever 37^a and also have the brake operating lever or rod 46^a disconnected from the clutch operating rod or bar 38^a and to permit such independent operation of the clutch with respect to the brake, the bar or rod 46^a is detachably connected to the upright portion of the shaft 44^a by means of a bolt 48^a as clearly shown in Fig. 11 of the drawings. The bolt 48^a has its free or threaded end 15 reduced to provide a shoulder, against which a washer 50^a abuts and is clamped, by means of a nut 51^a thus pivotally and detachably connecting the rods 46^a to the shaft 44^a. The links 36^a are connected to the lever 37^a by a bolt 48^a identical with the construction illustrated in Fig. 11 to permit disconnection between the levers 34^a and 37^a during the traction of the drilling machine if it is so desired.

20 25 By providing the brake pulley or drum 41^a upon the shaft 5^a and also by providing the detachable connection between the bar 46^a and the shaft 44^a this brake mechanism may be rendered inoperative or inactive 30 during the travel of the drilling machine, without necessitating the detaching of the brake mechanism as is necessary in the preferred form illustrated in Figs. 2 and 3 of the drawings.

35 Changes in details may be made without departing from the spirit of this invention, but;

I claim:

1. In a drilling machine, the combination, 40 of a portable supporting structure, traction wheels carried thereby, a power plant supported by said supporting structure, a drilling mechanism carried by the supporting structure, an operating pulley for said drilling mechanism, means operatively connecting the power plant and pulley, a transmission mechanism connected to said traction wheels, and removable means adapted to engage said pulley for connecting the pulley 45 to said transmission means for operatively connecting the power plant and traction wheels.

50 55 60 65 70 75 80 85 90 95 100 105 110 115 120 125 130 2. In a drilling machine, the combination of a portable supporting structure, traction wheels carried thereby, an internal combustion engine carried by said supporting structure, a drilling mechanism carried by the supporting structure, an operating shaft for said drilling mechanism, rotatably supported by the supporting structure, a pulley upon said shaft, a second shaft journaled in said supporting frame, means connecting said second shaft and said traction wheels for rotating the traction wheels by rotation of the second shaft, sprockets carried by said first and

second shafts and operatively connected for rotating the second shaft by rotation of the first shaft, the sprocket carried by said first shaft being rotatably mounted thereon, and pins adapted to extend through the sprocket carried by the first shaft and into said pulley to operatively connect the sprocket and the shaft.

3. In a drilling machine, the combination of a power plant, a clutch mechanism in said power plant, a drilling mechanism, an operating pulley for said drilling mechanism, means connecting said pulley and said power plant, a brake operatively connected to said pulley and means for simultaneously operating said brake and clutch.

4. In a drilling machine, the combination of a portable supporting structure, traction wheels carried thereby, a drilling mechanism carried by the supporting structure, a power plant carried by the supporting structure and including a clutch, means operatively connecting said power plant and said drilling mechanism, a brake interposed in said connecting means, means for simultaneously operating said brake and clutch and means engageable with said connecting means for operatively connecting said power plant and traction wheels.

5. In a drilling machine, the combination of a power plant, a clutch in said power plant, a drilling mechanism, an operating pulley for said drilling mechanism, means operatively connecting said power plant and said pulley, a brake drum operatively connected to said pulley, a brake band adapted for engagement with said brake drum, and means connected to said clutch and brake band for operating the brake simultaneously with operation of the clutch.

6. In a drilling machine, the combination of a power plant, traction wheels for said power plant, a clutch in said power plant, a drilling mechanism, an operating pulley for said drilling mechanism, means operatively connecting said power plant and said pulley, a brake drum operatively connected to said pulley, a brake band adapted for engagement with said brake drum, means connected to said clutch and brake band for operating the brake simultaneously with operation of the clutch, means engageable with said pulley to operatively connect the power plant and traction wheels.

7. In a drilling machine, the combination of a power plant, a clutch in said power plant, a drilling mechanism, an operating pulley for said drilling mechanism, means operatively connecting said power plant and said pulley, a brake drum operatively connected to said pulley, a brake band adapted for engagement with said brake drum, means connected to said clutch and brake band for operating the brake simultaneously with operation of the clutch, and removable means

4
to permit operation of said clutch independently of operation of the brake.

8. In a drilling machine, the combination of a frame, traction wheels for the frame, 5 drilling mechanism mounted on the frame, a prime mover on the frame, and a transmission mechanism associated with the prime mover and including an operating pulley

for the drilling mechanism and a sprocket wheel for the traction wheels, means for normally connecting the operating pulley to the prime mover, and a pair of removable pins engageable with the sprocket and the pulley for operatively connecting the same together for driving said traction wheels. 10

OTTO D. NORMAN.
